UNITED STATES PATENT OFFICE

HARRY H. WOLFE, OF COLUMBUS, OHIO, ASSIGNOR TO THE BUCKEYE STEEL CASTINGS COMPANY, OF COLUMBUS, OHIO

CAR COUPLER

Application filed April 10, 1929. Serial No. 354,001.

This invention relates to car couplers and more especially to a novel coupler shank.

It is well known that couplers, due to the severe buffing stresses to which they are subjected, decrease in length, and it has been found from investigations of couplers which have been in service for considerable periods of time, and also from test results, that most of the shortening of the shank takes place in the region extending from the butt end of the shank to the front end of the key slot. Due to the compression strains which the couplers are forced to undergo, the walls at the butt end portion of the shank have a tendency to bulge outwardly, and the butt surface acquires a concavity. Furthermore, this contraction of the shank may shorten the key slot to such a degree as to interfere with the ready insertion or removal of the key.

20 The primary object of the present invention is to overcome these disadvantages, and to provide improved reinforced coupler shanks for use with the A. R. A. standard or any other coupler head.

25 With the foregoing object outlined and with other objects in view which will appear as the description proceeds, my invention consists in the novel features hereinafter described in detail, illustrated in the accompanying drawings and more particularly pointed out in the appended claims.

Referring to the drawings,

Fig. 1 is a top plan view, partly in horizontal section, of one embodiment of my improved coupler shank.

Fig. 2 is a side elevation partly in vertical longitudinal section of the same.

Fig. 3 is a transverse vertical sectional view on the line 3—3 of Fig. 2.

40 Figs. 4 and 5 are views similar to Figs. 1 and 2, but of a modified form of the invention.

Fig. 6 is a transverse sectional view of the modified form, taken on line 6—6 of Fig. 5.

Fig. 7 is a transverse sectional view on the line 7—7 of Fig. 1.

In the embodiment of the invention shown in Figs. 1 to 3 inclusive, A indicates the hollow shank of a coupler, which is provided with parallel top and bottom walls 2 and 3, which may be of gradually increasing

thickness toward the key slot 4. The side walls 5 and 6 converge toward the key slot.

In the region of the key slot, I have reinforced the shank by extending webs or posts 7 and 8 from one side wall to the other, and by joining these key bearing posts, at the front and rear of the key slot, directly to the top and bottom walls 2 and 3 of the shank, as shown at 9 and 10. To permit this, the top and bottom walls 11 and 12 of the key slot 4, and the recesses or depressions 13 thus formed, are reinforced by ribs 14 which are integral with the portions 2, 3, 9, 10, 11 and 12.

As above stated, investigation of couplers in service, shows that, due to high buffing forces, the walls of the shank tend to bulge outward at about the section X—X, and this bulging in turn tends to draw the butt wall 15 inwardly, thus forming a concave bearing surface on the butt which considerable wear will not eradicate. Couplers in service about five years showed a strip about $\frac{3}{8}$ inches wide around the butt hole 16, which was not in bearing. To eliminate this difficulty, I have arranged a reinforcement 17 within the hollow butt end portion of the shank, and the vertical arms 18 of this reinforcement are integral with the top and bottom walls 2 and 3, the butt wall 15, and the neck portions 9 which join the top and bottom wall proper to the top and bottom walls 11 and 12 of the key slot.

The horizontal arms 19 of this reinforcement are integral with the side walls 5 and 6, the butt wall 15, and the horizontal post 7. These vertical and horizontal ribs 18 and 19, placed in the butt end portion of the shank, stiffen the walls, thus preventing bulging and shortening of the shank at this point. They also prevent the butt bearing surface from becoming concaved, and thus reducing the effective bearing area. It will be observed that the ribs 18 and 19 tie in the butt wall 15, all four shank walls and the rear key bearing post 7.

Instead of extending the top and bottom walls of the shank toward one another at the key slot portion of the shank, I may move the top and bottom walls of the key slot out, as shown at 20 and 21 in Figs. 4 to 6 inclusive,

to join the top and bottom walls 22 and 23 of the shank, and I prefer to do this in such manner that a gradual change of section is obtained. Full key bearing is provided for the full thickness of the key by arranging projections 24 on the walls 20 and 21, and extending these projections transversely entirely across the key slot 25. It will be noted that wide reinforcing ribs 26 form the upper and lower surfaces of the key slot, and act as wearing surfaces for the flat side of the draft key (not shown).

In both embodiments of the invention, I prefer to make the post 8 of gradually increasing thickness from its central portion toward its ends, and as best shown in Fig. 1, this post may be reinforced by vertical ribs 27, which are integral with the parts 2, 3, 8 and 10.

From the foregoing, it is believed that the construction, and advantages of the invention may be readily understood, and I am aware that changes may be made in the details disclosed, without departing from the spirit of the invention, as expressed in the claims.

What I claim and desire to secure by Letters Patent is:

1. A coupler shank having top and bottom walls, and provided with a key slot having top and bottom walls, the top and bottom walls of the key slot forming continuations of the top and bottom walls of the shank, certain of said walls being provided with depressions adjacent the key slot, and reinforcing ribs arranged in said depressions and integral with said walls of the shank and the walls of the key slot.

2. A hollow coupler shank including top, bottom and side walls joined at their ends to a butt wall, front and rear key bearing posts extending across the shank and having their ends integral with the side walls of the shank, top and bottom key slot walls having their ends merging into the top and bottom walls of the shank and said key bearing posts, and reinforcing ribs connecting said key bearing posts to the top and bottom walls of the shank, the top and bottom key slot walls being provided with depressions, and reinforcements arranged in the depressions and integral with the top and bottom key slot walls.

In testimony whereof, I have signed this specification.

HARRY H. WOLFE.
